CLAIM

The ornamental design for the protective football display case as shown and described.

DESCRIPTION

FIG. 1 is a left back side top down perspective view of the protective display case enclosing a football.

FIG. 2 is a right back side top down perspective view of the protective display case enclosing a football.

FIG. 3 is a front side view of the protective display case enclosing a football.

FIG. 4 is a back side view of the protective display case enclosing a football.

FIG. 5 is a left side view of the protective display case enclosing a football. The right side view of the protective display case enclosing the football is a mirror image of the left side view.

FIG. 6 is a top down view of the protective display case enclosing a football; and,

FIG. 7 is a bottom up view of the protective display case enclosing a football.

Broken lines are used to illustrate portions of the protective football display case that form no part of the claimed design. The other broken lines illustrate environmental subject matter that form no part of the claimed design. With the exception of the magnets, the protective football display case, including edges thereof, are made of transparent material.

1 Claim, 7 Drawing Sheets
